ELECTRICAL SYSTEM FOR PRODUCING MUSICAL TONES

Filed Nov. 5, 1928

BY
F. E. MILLER
ATTORNEY

UNITED STATES PATENT OFFICE

FRANK E. MILLER, OF NEW YORK, N. Y.

ELECTRICAL SYSTEM FOR PRODUCING MUSICAL TONES

Application filed November 5, 1928. Serial No. 317,219.

My invention relates to an improvement in a system for producing musical tones as disclosed in my United States Letters Patent No. 1,376,288 dated the 26th day of April, 5 1921.

Under the disclosure therein contained it is noted that the system produced primary monophonic music or music in which the fundamentals follow each other in sequence 10 or tone succession. In the practical construction of musical instruments under such a system it was usually necessary to use a separate loud speaker for each fundamental or harmonic note produced and it is my object herein to disclose a system in which any 15 note or musical notes, both fundamentals and sharps and flats and other harmonics may be produced not only simultaneously but also with the use of only one reproducing or loud 20 speaker unit. It will appear that as a result of my present disclosure I can produce chordal music and produce it with the use of only one reproducing unit or loud speaker. The advantage of this system is therefore 25 apparent.

A further object of my present invention is to introduce a better system of volume control so that I may control the volume of each particular octave as well as the volume of the 30 combined octaves. Furthermore it is a further object of my invention to introduce into the electrical system a plurality of "filters" which correspond to the "stops" of an organ so that by the operation of any one or more 35 of these filters in circuit I may change the quality of my tone to simulate the various notes of an organ for example such as the reeds or the brasses and even the stringed instruments.

40 My system will be more readily understood by reference to the accompanying drawing in which like letters and like numbers refer to like parts. The drawing shows a diagrammatic wiring diagram of the electrical system which I use for my musical instrument. Generically this system is the same as that disclosed in my previous patent, namely, one in which an oscillating circuit is used to 45 produce a musical note with the modification, 50 however, that my present wiring and con-

nections enable me to play any number of notes simultaneously through the instrumentality of one sound reproducing unit or loud speaker.

Referring to the drawing, Fig. 1 shows a 55 diagrammatic key board each key making contact from a conventional plus B source of electrical energy to 2, the key contactors, which are severally connected through the tuned inductance coil 3, having a variable iron wire 60 core for tuning in the plate circuit of the vacuum tube 7, 4 being a balancing condenser or capacity and 5 the primary of a transformer of which 6 is the secondary being a 65 high impedance output coil, the primary 5 65 being connected as shown in the grid circuit of the tube, the filament being connected to conventional source plus A and minus A, minus B being also conventionally connected as shown. Each of the squares S, S', etc., represent 70 the tubes and tube connections for each note of a given octave and each is the same except that they have different variations of inductance and capacity for each note to give them their proper values of frequency of 75 oscillation. Each octave is connected to a variable resistance 8 for the purpose of regulating volume. The octaves 9, 9' and 9'', etc., are connected as shown and thence through a further variable resistance 10 for 80 the purpose of main volume control, the circuit as shown then passing through the filter units 11, 12 and 13, each designed as shown with inductances and capacities either in series or parallel or both. These are connected to the amplifier input at 14 as shown and each filter may be regulated at the will 85 of the operator by proper stops and relays or both and they function to give different instrumental and solo effects or different qualities of tone. A is a conventional type 90 audio amplifier, preferably impedance coupled, which gives better coefficients for loading, quality and frequency. This amplifier is then connected at 15 to any conventional type of reproducing unit or loud speaker. It must, of course, be understood that additional amplifiers and loud speakers may also be connected for remote transmission to 95 strategically selected points especially in an 100

auditorium as well as for giving various "shading" effects and other effects.

Having thus described my invention, what I claim and desire to secure by United States Letters Patent is:

1. An electrical system for producing musical tones including a vacuum tube as a generator of electrical oscillations for each given tonal frequency and circuits associated therewith for each tonal frequency adapted to be connected to common reproducing units to simultaneously reproduce a chordal effect resulting from the simultaneous operation of any number of said circuits.

15 2. An electrical system for producing musical tones including a vacuum tube for each tonal frequency and circuits associated therewith for each tonal frequency all connected to common reproducing units to produce 20 chordal tones and a plurality of electrical filter circuits connected therewith to vary the quality of said tone.

25 3. An electrical system for producing musical tones including a vacuum tube for each tone frequency desired, circuits associated with the cold electrodes of said tube to oscillate; a transformer coupling in the grid circuit of each tube; the secondary of each transformer for each note connected in 30 common through a resistance volume control and through a plurality of filters to a common reproducing unit.

35 4. In an electrical music system, a plurality of oscillation generators for independently generating frequencies corresponding to the several notes of the musical scale, and means for so combining the outputs from the said oscillation generators as to produce chordal effects therefrom.

40 5. In an electrical music system, a plurality of oscillation generators for independently generating electrical frequencies corresponding to the several notes of the musical scale, means for so combining the outputs from the said oscillation generators as to produce chordal effects thereof, and a common sound reproducer for all of said generators for audibly reproducing the electrical tones generated.

50 6. In an electrical music system, a plurality of oscillation generators for independently generating electrical frequencies corresponding to the several notes of the musical scale, means for so combining the several frequencies generated by said oscillation generators as to produce chordal effects thereof, and a plurality of electrical filters connected with said combining means for varying the tone quality of the combined frequencies used to produce chordal effects.

60 7. In an electrical music system, a plurality of oscillation generators for independently generating electrical frequencies corresponding to the several notes of the musical scale, means for combining the output from

the oscillation generators in such manner as to produce chordal effects therefrom, a plurality of parallelly connected electric filter circuits connected with the combining means for said generated frequencies, means for connecting said parallelly connected filter circuits with the said combining circuit in such manner as to produce varying quality effects therefrom determinable by the filter circuit connected with the said combining circuit, 75 and a common sound reproducing system for audibly reproducing the electrical frequencies generated.

8. In an electrical music system, a plurality of oscillation generators for generating 80 frequencies corresponding to fundamental notes of music, and means for combining said oscillation of fundamental frequencies so as to create as a sound manifestation the effect of a chordal tone.

In witness whereof I have hereunto set my hand to these specifications this 31 day of October, 1928.

FRANK E. MILLER.
